UNITED STATES PATENT OFFICE.

EDWIN H. NELSON, OF DETROIT, MICHIGAN.

DESIGN FOR A BOTTLE.

SPECIFICATION forming part of Design No. 25,402, dated April 21, 1896.

Application filed March 10, 1896. Serial No. 582,653. Term of patent 7 years.

To all whom it may concern:

Be it known that I, EDWIN H. NELSON, a citizen of the United States, residing at Detroit, in the county of Wayne and State of Michigan, have invented and produced a new and useful Design for Bottles, of which the following is a specification, reference being had therein to the accompanying drawings, showing the same.

Figure 1 is an elevation of a bottle embodying my design. Fig. 2 is a plan thereof with the top rim of the neck broken off. Fig. 3 is a bottom plan, and Fig. 4 is an edge elevation, of the bottle.

The leading feature of my design is the novel configuration of the body, which consists of a facet-cornered prismatic portion A and a pyramidal facet-cornered portion B intermediate between the portion A and the usual cylindrical neck C. The cross-section of the body is substantially rectangular with

the corners cut off, which forms the facets D on the body, and the similar facets E are preferably formed around the base. The connection between the portions A and B is formed by distinct outlines. The four sides of the latter are, however, somewhat convex, and the convexity thereof increases toward the top, where they join with the cylindrical neck, and, in accordance with the taper of the portion B, the facets F formed thereon on the corners corresponding to the facets D also taper toward the neck.

What I claim as my invention is—

The design for a bottle as herein described and shown.

In testimony whereof I affix my signature in presence of two witnesses.

EDWIN H. NELSON.
